UNITED STATES PATENT OFFICE.

KEARNEY FELIX MITCHELL, OF SULPHUR, LOUISIANA.

AUTOMATIC DRILL-PIPE CUTTER.

Application filed August 15, 1927. Serial No. 212,935.

This invention relates to pipe cutters for use in cutting the drill pipe in an oil well when the pipe becomes stuck in the hole.

The object of the invention is to provide 5 an automatic drill pipe cutter, including a sleeve adapted to encircle the drill pipe and to be lowered into the well, the said sleeve carrying the cutting bits, and means for bringing the bits automatically into engagement with the work.

In the drawing

Figure 1 is a longitudinal sectional view of the pipe cutting tool as operatively mounted upon a drill pipe, the cutting bits 15 being disengaged from the pipe;

Figure 2 is a view similar to Figure 1, with the exception that the cutting bits are here shown in engagement with the pipe for cutting the same;

Figure 3 is a cross section on the line 3—3 of Figure 1.

The invention comprises a hollow, cylindrical shell 1, having an ordinary screw coupling 2 for connecting to a suitable 25 length of operating pipe 15 for lowering the device into the well (not shown). The upper end of the shell 1 is interiorly threaded as shown at 3, and a bit compressing collar 4 is formed to fit within the shell 30 1, and is threaded upon its outer periphery to loosely mesh with the inner threads 3 of the shell 1. Permanently mounted upon the upper end of the collar 4 is a coiled spring 5, the free or upper end of the said spring 35 being formed into a ring 6 from which extend the flexible and inwardly directed lock prongs 7, the said prongs being directed axially upward. The lower end of the collar 4 has its interior wall beveled off 40 conically, as shown at 8, the said wall feathering out towards the wall of the shell 1 at the lower portion of the collar 4. A pair of cutter bars 9 are pivoted at diametrically opposite points 10 upon the interior wall of the shell 1, substantially below the collar 4, the upper ends of the bars 9 being extended within the lower conical end of the collar 4 and being formed into inwardly directed bits 9'. The cutter bars 9 45 are normally forced asunder against the wall of the shell 1 by flat springs 11.

In use the device is lowered over the drill pipe 12, the prongs 7 expanding as they pass over the joint 13 to the drill pipe. The device is then partially retracted, whereupon 55 the upper or free ends of the prongs 7 engage the joint 13, thus compressing the spring 5 and thereby anchoring the collar 4 against rotation when the shell 1 is rotated. The shell 1 being now rotated, the collar 4 60 is caused to travel down the shell by virtue of the intermeshing threads 3 and 4, thus causing the lower tapered wall of the collar 4 to force the cutter bars 9 axially inwardly, and causing the bits 9' to bite into the pipe 65 12. Thus, the cutter bars 9 and bits 9' rotating with the shell 1, while the pipe 12 remains stationary, the resulting action is the cutting or severing of the pipe 12.

While I have herein described a certain 70 specific manner and method of constructing and assembling the elements of my invention, it is understood that I may vary from the same in minor details, not departing from the spirit of my invention, so as best 75 to construct a practical device for the purpose intended, as defined in the appended claim.

I claim:

A drill pipe cutter, comprising a cylindrical shell adapted for vertical disposition 80 within the well and over the drill pipe, the upper end of the shell being interiorly threaded; means for connecting the shell with an operating pipe; a bit compressing 85 collar threadably engaging the threaded upper end of the said shell, the lower end of the collar having its inner wall beveled off conically; a coil spring mounted upon the upper end of the said collar; lock prongs mounted 90 upon the upper end of the said spring; cutter bars pivoted oppositely upon the interior wall of the shell below the said bit compressing collar and having their upper ends extending upwardly within the said 95 conical lower end of the said bit compressing collar; inwardly directed bits at the upper ends of the said cutter bars; and means for normally forcing the cutter bars asunder.

In testimony whereof I affix my signature.
KEARNEY FELIX MITCHELL.
